UNITED STATES PATENT OFFICE.

LYNDE BRADLEY, OF MILWAUKEE, WISCONSIN.

AUTOMATIC STARTER FOR ELECTRIC MOTORS.

1,161,021.

Specification of Letters Patent. Patented Nov. 23, 1915.

Application filed August 10, 1911. Serial No. 643,329.

To all whom it may concern:

Be it known that I, LYNDE BRADLEY, a citizen of the United States, residing at Milwaukee, county of Milwaukee, and State of Wisconsin, have invented new and useful Improvements in Automatic Starters for Electric Motors, of which the following is a specification.

My invention relates to improvements in current controlling devices, with especial reference to that class of controlling devices disclosed in my former Patents, Number 723817, dated March 31st, 1903, 815317, dated March 13th, 1906, and 821697, dated May 29th, 1906. The general object of such devices is to provide means for progressively reducing the initial or protective resistance in the circuit of a motor or other electrically operated machine.

The object of this invention is to provide means, whereby the protective resistance in such electrical circuits may be automatically reduced and finally cut out entirely. The advantages thus secured reside not only in the fact that the operator is relieved of the necessity of operating a controller lever, but also in the fact that the reduction in the resistance is made uniformly gradual, and the variations are of less magnitude than they are apt to be where a controller lever is employed.

My invention is also peculiarly adapted for use in starting motors, since it provides means for varying the motor starting interval in proportion to the load.

In the drawings:—Figure 1 is a front elevation of a controller embodying my invention, showing the solenoid and relay in central vertical section, and the resistance column partially in vertical section. Figs. 2, 3 and 4 are diagrams illustrating the circuits as they are successively established during a motor starting operation, Fig. 2 illustrating the initial circuits, Fig. 3 the intermediate circuits, and Fig. 4 the final or normal working circuits.

Like parts are identified by the same reference characters throughout the several views.

The circuit of the motor 1 is closed by an ordinary switch 2. Initially, this circuit includes a variable resistance column 3 which may be assumed to be similar to those described in my former patents, above referred to. In my improved apparatus, however, I employ a solenoid 4 arranged in a

shunt circuit and operating through a lever 5 to apply pressure to the resistance column 3 during the motor starting period. During the motor starting period, the shunt circuit is controlled by a relay switch 6, the latter being included in circuit with the resistance column and also in the circuit of the motor. The relay operates to prolong the interval of pressure increase upon the column 3, by intermittently and momentarily interposing a high resistance 7 in the shunt circuit, sufficient to interrupt the effective flow of current to the solenoid winding, and for a period of insufficient duration to allow the solenoid core to return to its normal position and entirely relieve the pressure upon the column 3. The resistance 7 operates in substantially the same way as a circuit breaker, since it cuts out the electro-magnet by substantially interrupting the current in the shunt circuit. By the alternate operation of the solenoid and relay switch, I am enabled to apply a pressure to the resistance column 3 which increases step by step and but slightly at each step, whereby a substantially gradual or steady increase of pressure is secured. During the final upward movement of the solenoid core, the pressure upon the column 3 reaches a maximum, and the resistance of said column to the passage of current reaches the minimum, whereupon the solenoid actuates a switch member 8 into circuit closing relation with a contact member 9 to cut out both the resistance column 3 and the relay switch 6, the motor being then substantially at full speed.

The resistance column 3 is, as above stated, similar to those shown and described in my former patents. But for my present purposes it is preferably mounted upon the lever 5 and lifted bodily thereby. At its upper end, it is provided with a head block *a*, having a stem *b* adapted to bear against a resilient stop *c*. A cap *d* covers the top of the column and is provided with depending annular flanges *e*, *e'*, the outer flange *e* embracing the upper end of the column inclosing casing, and the inner flange *e'* fitting an annular channel in the cap block, thus preventing a free passage of air to the interior of the casing without sealing the casing against the escape of air or gas when the column is heated.

The relay is wound for a predetermined amperage and is included in the circuit of the column 3. When the resistance of the

column is reduced by pressure, as above explained, the relay armature will be actuated as soon as the volume of current is sufficient, and this separates contact member *g* from the stationary contact member *h*. Initially, the circuit of the motor, (Fig. 2) is from the switch through line 10, column 3, line 11, the winding of the relay, line 12 to the motor, and line 13 to the switch, the shunt circuit being through line 14 to the solenoid 4, line 15, contacts *g* and *h*, and line 16. But when the relay armature lifts,—separating contacts *g* and *h*, (Fig. 3) the electrical connection of line 15 is to the high resistance 7 and by line 17 to contact *h*.

The solenoid core *i* moves downwardly by gravity when the current to the solenoid is checked by the resistance 7, and this causes an instant diminution of pressure upon column 3, with consequent increase in resistance and a reduction in the volume of the current through relay 6, sufficient to permit its armature to descend until *g* and *h* are again in contact, thus restoring the shunt circuit of Fig. 2 and causing another upward movement of the solenoid armature. These alternative oscillations of the relay and solenoid armatures continue until the solenoid core *i* actuates switch member 8 into engagement with contact 9, whereupon the circuit of the motor will be (Fig. 4) from switch 2 through line 10 through lines 14 and 19, contacts 9, switch member 8 and lines 20 and 12 the motor, and the line 13 to the switch. The shunt circuit through the solenoid 4 then is as shown in Fig. 4, while switch 2 remains closed.

While I have shown and described the resistance column 3 as similar to those shown in the above mentioned former patents, it will be understood that any suitable variable protective resistance may be employed, and I therefore do not limit my claims to a resistance column of specific type. Neither is the specific structure and arrangement of the various parts regarded as essential, although I prefer to employ a lever 5 to lift the column against a cushioned stop *C* and to allow the units to separate by gravity when the pressure is relieved. A resilient stop is provided in order to avoid shocks, and for the same reason the solenoid core *i* is connected with lever 5 by a yielding link comprising a rod *l*, which extends through a slot in the lever, and carries a coiled spring *l* which supports a movable lever engaging block *m*.

27 are fuses of ordinary construction.

With this invention the duration of the interval of progressive resistance column compression is proportioned to the time required for developing full speed in the motor, that is to say, it depends in duration upon the load. This is due to the fact that the relay will continue to cut out the sole-

noid (interpose the high resistance), until the speed of the motor reaches a point where the counter electro-motive force will develop to such an extent as to hold the amperage below that required for relay operation. As the speed of the motor increases, the solenoid core successively moves to higher and higher points until the maximum pressure is exerted upon the resistance column, and until said column, with the relay, are cut out as above explained. The armature core *i* is preferably arranged to serve as a plunger in the solenoid cavity. Packing rings 24 may be employed to prevent the free entry and escape of air, to and from this cavity, thus checking the momentum of the core in either direction to prevent injurious pounding.

Means for adjusting the relay to operate at different amperages, are preferably provided. This is simply accomplished by providing an adjustable support for the contact member *h*, which member serves as a stop limiting the downward movement of the armature. To this end the stop *h* is supported by a screw 25, and a lock nut 26 employed to secure it in any desired position of vertical adjustment.

I claim:—

1. An electric current controller, comprising the combination with a main electrical circuit, of a variable resistance member in said circuit, electro-magnetic mechanism operatively connected therewith to vary the resistance, and a relay switch in said main circuit, operatively arranged to interrupt the effective flow of current to the electro-magnetic mechanism sufficiently to temporarily render the electro-magnet inoperative. 95

2. An electric current controller comprising the combination with a main electrical circuit, of a relay switch and a variable resistance column included in said circuit, electro-magnetic mechanism included in a shunt from said main circuit, and adapted 110 to vary the pressure upon said column, and means for utilizing the relay switch to interrupt the flow of effective current to said electro-magnetic mechanism whenever the flow of current through the relay exceeds a 115 predetermined limit, whereby a partial reduction of pressure upon said column is permitted during each operation of the relay switch.

3. An electric current controller, comprising the combination with a main electrical circuit, of a relay switch and a variable resistance member included in said circuit, electro-magnetic mechanism included in a shunt from said main circuit, and adapted 125 to vary the resistance of said member in the main circuit, and means for utilizing the relay switch to interrupt the effective flow of current in said shunt circuit whenever the flow of current through the relay 130

exceeds a predetermined limit, together with means controlled by the electro-magnetic mechanism during a final operation thereof, for cutting out the relay switch and 5 resistance member from the main circuit.

4. An electric current controller, comprising the combination with a main electrical circuit, of a variable resistance column included in said circuit, a shunt circuit auxiliary to said main circuit, electro-magnetic mechanism in said shunt circuit, adapted to compress the variable resistance column, and means for prolonging the interval of varying resistance, by temporarily relieving 15 the movable parts of said mechanism from the electro-magnetic pull.

5. An electric current controller, comprising the combination with a main electrical circuit, of a variable resistance member included in said circuit, a shunt circuit auxiliary to said main circuit, electro-magnetic mechanism in said shunt circuit, and controlling the variable resistance member, and means for prolonging the interval of electro-magnetic control by intermittently interrupting the effective current in said shunt circuit, and temporarily relieving the resistance member of such control.

6. An electric current controller, comprising the combination with a main electrical circuit which includes a variable resistance column in which the resistance is reduced by compression, of a solenoid in shunt circuit from said main circuit, a switch adapted to be operated by the solenoid, when energized, to cut out said resistance column, a relay switch, energized by the current in the main circuit to release the solenoid core from magnetic pull when the main circuit current exceeds a predetermined volume, and means, 40 operated by said solenoid, for progressively compressing the resistance column preparatory to cutting it out of said circuit.

7. An electric current controller, comprising the combination with a main electrical circuit having a variable resistance column included therein, and in which the resistance is reduced by compression, of a lever supporting said column, a yielding stop between which and the lever, the column may be compressed, a solenoid having a movable member connected with the lever, shunt connection for intermittently energizing said solenoid from the main circuit, a switch for cutting out said resistance column, controlled by said solenoid during the final movement of the movable member, and means for delaying the movement of said movable member during the compressing operation.

8. An electric circuit controller, comprising the combination with a main circuit, of a current regulating member, electro-magnetic mechanism for controlling said member and adapted to both increase and de-

crease its effectiveness for current regulation, a switch adapted to be operated by said mechanism to cut out said member from said main circuit, and a relay switch in said circuit adapted to interrupt and reestablish 70 the effective current delivered to the electro-magnetic mechanism in accordance with the number of amperes delivered.

9. An electric current controller, comprising the combination with a main circuit, of a variable resistance column included in said circuit, electro-magnetic mechanism in shunt with said circuit and operatively connected to vary the resistance of said column, a relay switch in circuit with the resistance column, and a high resistance member adapted to prevent effective current delivery to the electro-magnetic mechanism, said relay switch being adapted to operate under a predetermined current volume to temporarily 85 interpose the high resistance member in said shunt circuit when the current in the main circuit exceeds a predetermined volume.

10. An electric current controller, comprising the combination with a main circuit having a variable resistance member included therein, of a solenoid provided with a movable core operatively connected to vary the resistance of said member, a current controlled switch for substantially deenergizing said solenoid when the current in the main circuit exceeds a predetermined volume, and a switch member in the path of the solenoid core adapted to be actuated during the final movement thereof in one direction to cut out 100 said current controlled switch and resistance member from the main circuit.

11. The combination with a motor circuit, of a resistance column in said circuit, electro-magnetic means for progressively compressing the same, and a relay switch for intermittently interrupting the effective current supply to the electro-magnetic mechanism during the motor starting interval.

12. The combination with a motor circuit, of an electro-magnetically compressed resistance member in said circuit, and electrically operated means for alternately increasing and decreasing the pressure upon said member during the motor starting interval to 115 regulate the current to the motor and also lengthen said interval.

13. The combination with a main circuit, and a variable resistance column in said circuit, of electrical means for varying the resistance of said column and electrical means also included in the main circuit for successively interrupting the effective supply of current to the resistance varying means to 120 prolong the period of variation.

14. The combination with an electrical circuit, of a variable resistance member, electro-magnetic controlling mechanism therefor, a member for automatically relieving said controlling mechanism of effective magnetic in- 125

- fluence in successive brief intervals while permitting progressive variation of the resistance during the intermediate periods, and a device operated by the controlling mechanism during its final resistance varying movement, for cutting out the variable resistance and relieving members from said circuit.
15. An electric current controller, comprising the combination with a main electrical circuit, having a variable resistance column included therein, electro-magnetic means for varying the pressure upon said column to both increase and decrease such pressure at intermediate stages of a set of gradually increasing pressure changes, and a switch for cutting out said column from the electrical circuit, controlled as to operation, by the electro-magnetic means during the final pressure applying operation.
16. An electric current controller, comprising the combination with a main electrical circuit, having a variable resistance column included therein, electro-magnetic means for varying said resistance by successively applying increased and reduced pressures to said column with accumulating increased pressure, and means, controlled by said electro-magnet, for cutting out the resistance column from said main circuit, when the pressure thereon exceeds a predetermined maximum.
17. An electric current controller, comprising the combination of a variable resistance medium in which the resistance is varied by compression, electro-magnetic means for compressing said medium, means adapted to be controlled by the current volume passing through the resistance medium for checking the operation of the electro-magnetic means at any and all times during the compressing operation, whereby the resistance of said medium is subjected to constant and continuous current volume control during the compression period.
18. An electric current controller, comprising the combination with a main electrical circuit, of a variable resistance member included in said circuit, electro-magnetic means for operating said member to vary the resistance, relay switch mechanism in said circuit for intermittently interrupting the effective current to the electro-magnetic
- means to delay the period of resistance variation, and means for adjusting said relay switch mechanism to operate under different conditions of current volume.
19. An electric current controller, comprising the combination with a main electrical circuit having a variable resistance column included therein, and in which the resistance is reduced by compression, of a lever supporting said column, a yielding stop between which and the lever, the column may be compressed, a solenoid having a movable member connected with the lever, shunt connections for energizing said solenoid from the main circuit, a switch for cutting out said resistance column, controlled by said solenoid during the final movement of the movable member, and means for operating said movable member in two directions during the compressing period to increase and decrease the pressure, together with means for pneumatically cushioning the movable member of the solenoid.
20. An electric current controller for motor circuits, comprising the combination of a variable resistance medium, in which the resistance is varied by compression, an electro-magnetic device having a movable member for compressing said medium, said device being adapted to respond constantly during the compressing period to variations of current volume in the motor circuit, means for cutting out said medium from an electrical circuit at a predetermined stage of compression, and means for pneumatically cushioning the movable member of the electro-magnetic device.
21. The combination with a motor armature circuit, of a compressible resistance member in said circuit, a solenoid having a movable core provided with connections adapted to apply pressure to the resistance member, and a relay in the motor armature circuit adapted to regulate the movement of the solenoid core in accordance with the current volume in said armature circuit.
- In testimony whereof I affix my signature in the presence of two witnesses.
